UNITED STATES PATENT OFFICE.

VINCENT P. RUMELY, OF DETROIT, MICHIGAN.

TOOL FOR ADJUSTING POINTS OF SPARK PLUGS.

Application filed October 4, 1924. Serial No. 741,697.

The present invention relates to a tool for producing a uniform gap between the points of spark-plugs for internal combustion engines. As is well known in engines of this type the ignition is supplied to the explosive mixture confined within the cylinders by means of spark-plugs between the points of which an electric spark is passed. This gap between the points of the spark-plugs should be of a certain width to produce the most effective ignition.

The object of my invention is to provide a tool by which the points of spark-plugs can be adjusted to have a uniform width of gap between them in a convenient manner and by a single operation of the tool.

The invention will be fully understood from the following description when taken in connection with the accompanying drawings, and the novel features thereof will be pointed out and clearly defined in the claims at the close of this specification.

In said drawings:

Fig. 1 shows a spark-plug point adjusting tool embodying my invention, the jaws of the tool being open;

Fig. 2 is the same as Fig. 1, with the jaws of the tool closed;

Fig. 3 is a side view taken from the left of Fig. 2, and Fig. 4 an end view of the jaws also taken on Fig. 2;

Fig. 5 shows the opposite side of the tool from that shown in Figs. 1 and 2, the construction being slightly modified;

Fig. 6 is a section taken in the direction of the arrow on the line 6 of Fig. 5; and

Fig. 7 shows the tool as applied to the points of a spark-plug.

Referring now to Figs. 1 and 2, the tool comprises two members 11 and 12 pivoted at 13 and provided at one end with cooperating jaws 14 and 15 and arms 16 and 17 at the other end. The construction shown and so far described is the ordinary construction of a pair of pliers, but it will be understood that my invention may be applied to any device having cooperating jaws which can be moved toward one another.

As shown in Figs. 1 to 4, a plate 18 is secured to the jaw member 14, so as to be integral therewith (see particularly Fig. 4) and to extend beyond the face 21 of said jaw member 14. A spacer or second plate 19 is fixed to the plate 18 at right angles therewith so as to project between the jaw members 14 and 15 and in a position such

that if extended it would pass through the center *a* of the pivot 13. The spacer 19 extends slightly beyond the ends of the jaws 14 and 15 and the edge of the plate 18 and serves as a guide for the spark plug points which are introduced on opposite sides of the said spacer.

When the plate 18 is thus permanently fastened to the jaw 14, a space 20 is left between the spacer 19 and the face 21 of the jaw 14, the space 20 being slightly greater than the size of stock of which the points 23 and 24 of the spark plug 25 are made, thus permitting either of said points to be inserted easily.

In the modified construction shown in Figs. 5 and 6 the plate 18, instead of being attached to one of the jaw members 14 or 15, as in Fig. 1 to 4, is secured to the pivot 13, in any suitable manner as by a screw 26, the said plate being free to swing about the pivot 13 except as restrained by the limits of the movement of the spacer or second plate 19 between the cooperating faces 21 and 22 of the jaws 14 and 15. In this construction, as well as in that previously described, the spacer 19 extends beyond the end of the plate 18. This projection assists the introduction of the parts of the spark plug on opposite sides of the said spacer 19, irrespective of the position which the plate 18 and the spacer 19 may have assumed with respect to the jaws 14 and 15 when the latter are opened.

The spacer 19 is made of a thickness equal to the width of the gap which it is desired to have between the points 23 and 24 of the spark plug. In using the tool the points of the plug are inserted on opposite sides of the spacer 19 and the jaws 14 and 15 brought together. The points 23 and 24 are thereby pressed against the sides of the spacer 19 and are bent so that when removed a space determined by the thickness of the spacer 19 is left between them.

The tool above described is of very great value, especially to automobile manufacturers and repair men to whom spark plugs are frequently shipped in bulk rather than in individual cartons which would protect the points. Although the points of the spark plugs may have been adjusted originally, it is, therefore, necessary that they be again adjusted before being put in use. My invention provides a convenient and accurate tool for producing this necessary adjustment

quickly thereby saving considerable time and labor.

What I claim as my invention is:

1. A tool for adjusting the points of spark plugs, comprising a pair of movable jaws and an externally supported spacer member consisting of angularly disposed plates, one of which plates extends between said jaws and is adapted to receive the points of a spark plug on opposite sides thereof to provide a predetermined gap between said points when said jaws are moved toward one another.
2. A tool for adjusting the points of spark plugs, comprising a pair of pivoted jaws, arms for moving said jaws toward one another; and a spacer member comprising angularly disposed plates, one of which is positioned between said jaws and supported externally thereof, and adapted to receive the points of a spark plug on opposite sides thereof to provide a predetermined gap between said points when said jaws are moved toward one another.

3. Pliers for adjusting the points of spark plugs, comprising two members pivoted together to provide cooperating jaws on one side of the pivot, arms on the opposite side of the pivot for moving said jaws toward one another, and a spacer member comprising a pair of angularly disposed plates, one of said plates being positioned between said jaws, said spacer being adapted to receive the points of a spark plug on opposite sides thereof to provide a gap of predetermined amount between said points.

4. A tool for adjusting the points of spark plugs, comprising a pair of pivoted jaws, arms for moving said jaws toward one another; a plate on one side of the jaws, and a spacer member on said plate and extending between the jaws to permit the points of a spark plug to be positioned on opposite sides thereof to provide a gap of predetermined amount between said points when said jaws are pressed together.

In testimony whereof I affix my signature.
VINCENT P. RUMELY.
